UNITED STATES PATENT OFFICE.

SAMUEL LIONEL JEFFERIES, OF GAFFNEY, SOUTH CAROLINA.

DENTAL CASTING MACHINE.

Application filed October 15, 1921. Serial No. 508,011.

To all whom it may concern:

Be it known that I, SAMUEL LIONEL JEFFERIES, a citizen of the United States, and a resident of Gaffney, in the county of 5 Cherokee and State of South Carolina, have invented certain new and useful Improvements in Dental Casting Machines, of which the following is a specification.

My invention relates to a dental casting 10 machine.

The object of the invention is to provide a machine of the above character by which the fusing of gold, porcelain, or like material from which teeth are formed and the casting 15 of a tooth may be accomplished in one operation.

It is also an object of the invention that the machine be adapted to be easily operated.

20 It is a further object of the invention that the machine be extremely simple in construction and inexpensive to manufacture.

Other objects and advantages of the invention will hereinafter appear.

25 The invention is illustrated by way of example in the accompanying drawings, in which,

Figure 1 is a vertical sectional view exemplifying the embodiment of the present 30 invention.

Figure 2 is a top plan view of the crucible table.

Figure 3 is a detailed view illustrating a modified form for lifting and lowering of 35 the crucible table.

Figure 4 is a view in side elevation of a modified form of the dental machine and showing the supporting bench or table in section.

40 Figure 5 is a view similar to Figure 4 and showing a still further modification of the dental machine.

Figure 6 is a detailed view illustrating a modified form for compressing the fused 45 material in the mold.

Referring to the drawings in detail and particularly to Figures 1 and 2, 10 indicates generally a work bench or the like and 11 a floor therebeneath. Upon the work bench 50 10 there is provided a plurality of vertical posts 12 which support a plate 13, said posts being preferably formed by bolt and telescoping sleeve as shown, said bolts being adapted to solidly secure the plate 13 to the bench 10; and the plate 13 is preferably rectangular in shape. The plate 13 and bench

10 are provided with registering openings 14 through which there extends the forks or arms 15, said forks terminating at their lower ends in a shank 16, the free end of which is bifurcated and having pivoted between bifurcations one end of a ball crank lever 17 by means of a rivet or the like, as at 18. The bell crank lever 17 is fulcrumed between a pair of standards 19 by the means 60 of a pin as at 20, the standards 19 being formed with a base plate 21 which is secured to the floor by means of nails or the like as indicated at 22. Upon the other end of the bell crank lever 17 there is provided a foot 70 pedal 22' by which the same may be depressed.

The free ends of the forks 15 are connected by a plate 23, said plate being formed with a central circular opening 23' in which 75 there is disposed and secured a grid 24, said grid consisting of the radial plates 24', which extend from the periphery of the opening 23'.

Upon the plate 23 there is secured an asbestos sheet generally designated by the reference numeral 25, said sheet having a central opening adapted to register with the opening 23' of the plate 23 and being secured in position by means of rivets or the like as indicated at 26. Within the opening 23' of the plate 23 there is fitted a cylindrical crucible 27 in which there is provided a mold 28, said mold having formed therein a casting cavity 29 which communicates 90 with the upper surface of the mold through the orifice 30. Also the upper surface of the mold is dished as shown in Figure 1.

Upon the plate 13 there is positioned a pair of posts 31 which are preferably 95 squared in cross section and each post terminating in its upper end in a reduced threaded portion 32. The posts 31 have each arranged longitudinally thereof a plurality of openings 33 which are adapted for receiving the pins 34, the purpose of the pins being to provide means whereby the plate 23 may be held in different positions. The posts 31 also support a plate 35, said plate being secured in position by nuts 36 100 carried by the ends of the posts 31. Beneath the plate 35 there is disposed a cap 37 which is adapted to fit upon the cylindrical crucible 27, said cap having formed upon its upper face a nipple 38 which extends upwardly through the plate 35 and adapted to 105 permit vertical movement of the cap 37. At

any suitable and convenient point a tank 39 is positioned adapted to hold a supply of compressed air and from this tank there is extended a pipe 40 which extends through the 5 nipple 38 of the plate 37 and carries a valve 41 which is adapted to be operated for opening the pipe 40 through the handle 41' and link 39' so that air may escape therethrough into the crucible 27 upon the upward movement of the cap 37 and normally held closed by the spring 40'. Also the pipe 40 may have interposed therein a valve 43 by which the compressed air from the tank 39 may be controlled.

15 Between the forks 15 there is supported a table 44' upon which a burner 45 may be seated for applying its flame beneath the mold 28. Also the burner may be connected with a fuel supply hose as at 46 which may 20 extend through an opening 44 in the table 44' and thus permit the burner to be raised and lowered with the crucible 27.

In the operation of the present casting machine, assuming that it was intended to 25 cast a tooth of a determined size and shape then the proper mold 28 is located and placed in the crucible 27 and the proper amount of porcelain, gold or the like is placed upon the mold. The burner 45 is 30 placed in position and after the metal or porcelain has melted on the top of the mold then further pressure is exerted upon the foot pedal 22' to bring the crucible beneath the cap 37 and force the same upwardly 35 whereupon the valve 41 is operated to permit air pressure to be applied upon the fused porcelain or metal and force the same through the orifice 30 into the cavity 29 and thus cause a solid tooth or the like to 40 be cast.

Upon decrease of pressure upon foot 45 pedal of plate 22' the table 23 can again move downward and thus permit the valve 41 to close. The mold 28 may now be removed and separated so that the tooth cast can be likewise removed, that is after the same has been properly cooled.

Referring to Figure 3, 47 indicates a bell 50 crank lever similar to the lever 17 indicated in Figure 1, which in this instance, however, is fulcrumed or pivoted as at 48 to a downwardly extending bar 49. Also the lever is formed with a knurled handle 50 at its other end so that the same may be hand-operated for moving upward and downward 55 the crucible table support generally indicated by the reference numeral 51. Numeral 52 indicates the laboratory table similar to that indicated by the reference numeral 60 10 in Figure 1.

Referring to Figure 4 in which a modified 65 means is shown for raising and lowering the crucible 27 it will be seen that each of the posts 31 rotatably support a pinion 53 which is adapted to mesh with a rack 54

extending downwardly from each end of the crucible table 23. Upon one of the posts 31 there is pivoted a handle 55 which has projected therefrom adjacent its upper end 70 a finger 56 and the free end of the finger being disposed in between a pair of adjacent teeth of the associated cog wheel 53. As is obvious by this arrangement when it is desired to move the crucible table upwardly it is only necessary to draw downwardly 75 upon the handle 55 and when it is desired to move the crucible table downwardly then this operation is merely reversed.

Referring to Figure 5 of the drawings the construction shown is substantially the same as illustrated in Figure 4 and like reference numerals refer to similar parts. In this instance, however, one of the cog wheels 53 is formed upon a large circular plate member indicated by the reference numeral 56 which has a handle as indicated at 57 extending at right angles thereto and by which the apparatus or machine may be manipulated.

Referring to Figure 6, the purpose of this 90 illustration is to show a modified means for forcing the fused metal or porcelain into the mold. In this instance the numeral 58 indicates a plate similar to the plate 35 shown in Figure 1 which is supported in the same manner and has formed upon the lower face thereof a hemi-spherical shaped cup 59. This cup is in alignment with the crucible 60 and it is supported by the plate or table 23 described in Figure 1. The 95 crucible 60 has disposed therein its mold 61 in which is formed the cavity for molding a tooth or the like and which communicates with the upper surface of the mold through an orifice as shown in Figure 1. In this instance the cup 59 is filled with asbestos, wet paper or other material similar in character and upon the upward movement of the crucible table this wet paper or the like will engage the crucible and press downwardly 100 upon the fused metal upon the upper surface of the mold 61 and force the same into the cavity therein for forming a solid tooth casting.

While I have herein shown and described 115 the preferred form and likewise modified forms of my invention, I wish it to be understood that I am aware of the fact that the general arrangement, combination and construction of parts may be changed by those skilled in the art without departing 120 from the spirit of my invention as indicated by the appended claims.

What I claim is:

1. A dental casting machine of the character described, comprising a table, means for manually raising and lowering said table, a crucible supported by the table, and adjustable means for supporting said table 125 in a raised position.

2. A dental casting machine of the character described, comprising a table, means for manually raising and lowering said table, a crucible supported by said table, a cap supported above the table adapted to fit upon the crucible when said table is moved upwardly to bring the crucible into engagement with said cap, a source of compressed air supply, and means whereby compressed air will be automatically permitted to enter the cap upon the table being raised a predetermined degree. 5
3. A dental casting machine of the character described, comprising a table, means for manually raising and lowering said table, a crucible supported by said table, a cap supported above the table adapted to fit upon the crucible when said table is moved upwardly to bring the crucible into engagement with said cap, said cap being adapted to move upwardly, and means whereby the upward movement of the cap a predetermined degree will cause compressed air to enter the interior of said cap. 10
4. A dental casting machine of the character described, comprising a table, means for manually raising and lowering said table, a crucible supported by the table, a plurality of stationary posts extending above said table, a cap supported by said 15
- posts, and means carried by said posts whereby the height of the table may be adjusted. 20
5. A dental casting machine of the character described, comprising a table, means for manually raising and lowering said table, a crucible supported by the table, a plurality of stationary posts extending above said table, a cap supported by said posts, and pin means adapted to be adjustably raised upon said post for supporting the table in a raised position. 25
6. A dental casting machine of the character described, comprising a table, a foot lever for raising and lowering said table, a crucible supported by the table, and means for adjustably supporting said table in a raised position. 30
7. A dental casting machine, comprising a stationary table, a plurality of rods extending upwardly through guide openings in said table, a foot lever for raising and lowering said rods, a crucible table supported by said rods, a crucible cap supported above said table, and means whereby a burner may be supported upon the first named table to apply a heat beneath the crucible table when said crucible table is in a raised position. 35

SAMUEL LIONEL JEFFERIES.
